SAMPLING DEVICE

W. Norman Oswald, Dallas, Tex., assignor to
 Houston Oil Field Material Company, Inc.,
 Houston, Tex., a corporation of Delaware

Application November 17, 1939, Serial No. 304,919

3 Claims. (CL 255—1.4)

This invention relates to new and useful improvements in sampling devices.

One object of the invention is to provide improved means for securing samples of the drilled formation without necessitating the removal of the drill bit or stem from the well hole, said means being primarily designed for the acquisition of side wall samples.

An important object of the invention is to provide an improved sampling device which is adapted to be connected in the usual drill stem and which includes means for obtaining a sample of the formation being drilled, said means being arranged so as to be insertable within and removable from said drill stem by a wire line, whereby a sample may be obtained at any point within the well hole.

Another object of the invention is to provide an improved sampling device having removable means for closing off the bore thereof during the usual drilling operation, whereby drilling fluid may be circulated directly to the cutting faces of the drill bit in the conventional manner.

A particular object of the invention is to provide an improved device, of the character described, including a body having a drill bit made integral therewith and arranged to be secured to the lower end of a drill stem, the body being provided with means for by-passing the drilling fluid to the bit during the drilling operation and also having a bore communicating with the drill stem through which a sampling tube may be lowered so as to project laterally from said body into engagement with the well bore, whereby a sample of the formation adjacent said bit may be taken at any time.

A further object of the invention is to provide an improved sampling device having a bore which communicates with the well hole through a radial opening, the bore being adapted to receive a sampling tool which is arranged to be lowered thereto by a wire line, there being co-acting means on the tool and within said bore for holding the tube carried by the lower end of said tool in position within the radial opening, whereby lowering of the drill pipe will cause said tube to engage and take a sample of the adjacent formation; the co-acting holding means being so arranged that raising of the tool by its upper end will automatically disconnect said means so as to readily permit removal of said tool.

Still another object of the invention is to provide an improved device, of the character described, wherein its bore is arranged to receive a sampling tool having a tube pivotally secured to its lower end, said bore having means disposed therein for orienting the tube, whereby the proper operation of the same is assured and a more rugged device is provided.

A construction designed to carry out the inven-

tion will be hereinafter described, together with other features of the invention.

The invention will be more readily understood from a reading of the following specification and by reference to the accompanying drawings, in which an example of the invention is shown, and wherein:

Figure 1 is a view, partly in elevation and partly in section, of a sampling device constructed in accordance with the invention and shown connected to the lower end of a drill stem with its bore closed by a plug,

Figure 2 is a vertical, sectional view of the device with a sampling tool positioned within the bore thereof in place of the plug,

Figure 3 is an enlarged horizontal, cross-sectional view, taken on the line 3—3 of Figure 2,

Figure 4 is a similar view taken on the line 4—4 of Figure 2,

Figure 5 is a vertical, sectional view of a portion of the sampling device showing the sample tube extended in sample obtaining position,

Figure 6 is a view similar to Figure 2, and taken at a right angle thereto,

Figure 7 is an enlarged view, partly in elevation and partly in section, of the upper end of the device, with the latch engaging one of the annular grooves to prevent upward displacement of the sampling tube,

Figure 8 is a similar view showing the latch disengaged preparatory to removal of the tube, and

Figure 9 is an enlarged isometric view of the sampling tube, showing its connection to the tool.

In the drawings, the numeral 10 designates a drill pipe or tubing having a sampling device A, constructed in accordance with the invention, mounted on its lower end for the purpose of taking formation samples from the side wall of the well bore. The sampling device includes an elongate drill body 11 having an axial bore 12 which opens into the bore of the tubing 10 and extends therethrough from the upper portion of said drill body to a point spaced above the lower extremity thereof. The lower end of the bore 12 communicates with a longitudinal recess 13 which in turn communicates through one side of the drill body with the well bore. An inclined deflector member 14 extends across the lower portion of the recess 13 and has its upper surface dished and inclined outwardly toward the vertical wall of the well bore. A suitable coil spring 15 is positioned beneath the member 14 so as to urge it upwardly and outwardly. The deflector member is preferably hinged to the back wall of the recess, as will be hereinafter explained.

The lower extremity of the drill body is provided with a suitable drill bit 16, which may be of any desired type as called for by the formation through which the well is being drilled. A fish tail bit is shown in the drawings for illustrative

purposes, but any other type of drill bit could be used without affecting or deterring from the operation of the sampling device. As the drill bit bores through the earth, particles of formation pass upwardly past the sampling device. In order to prevent these particles from entering the bore 12 and clogging the same, a plug 17 is suitably positioned within said bore. When it is desired to take a core sample, the plug 17 is removed and replaced with a sampler 18. The sampler is formed with an elongate upper portion or mandrel 19 and has a cylindrical sampling tube 20 pivoted to its lower extremity. To obtain a core sample, the sampler is lowered into the bore 12 until the hinged sampling tube strikes the deflector member 14 and is swung outwardly into engagement with the well hole formation. Suitable anchoring means are provided in the upper portion of the sampler whereby the latter is securely anchored within the bore 12. Downward movement of the sampling device will force the sampling tube further into the formation so that a core sample is forced within said tube. Subsequent raising of the upper portion of the sampler will release the anchoring means and allow the sampler, along with the core sample, to be withdrawn from the bore 12 and the well hole by a wire line or other suitable means.

The sampling device may be suspended from the tubing string 10 in any desirable manner. It is preferable, however, to suspend the former from a tool joint or sub 21 which is in screw-threaded engagement with the lower extremity of said tubing and has a screw-threaded pin 20' formed on its lower end. An axial bore 22 extends through the sub 21 and has its extreme upper end enlarged so as to provide a counterbore having substantially the same diameter as the bore of the tubing. The enlargement of the bore forms an annular shoulder 23, which is beveled to prevent the sampling tube from catching or engaging thereon in its downward passage. A plurality of annular grooves or recesses 24 are disposed within the internal surface or wall of the counterbore below the shoulder 23 and have their back walls tapering downwardly toward the axis of said bore. The upper ends or walls of the grooves are inclined upwardly and inwardly, thereby forming annular shoulders 25, the purpose of which will be explained hereinafter.

The drill body 11 carries an internally screw-threaded box 26 in its upper end, said box being engaged by the pin 20' and securely fastening the drill body to the lower end of the sub 21. The upper and lower portions of the body are substantially circular in cross-section, while the intermediate or central portion thereof is flattened on diametrically-opposed sides, forming flat, vertical surfaces 27 on each side of said body. As pointed out hereinbefore, the drill body has an axial bore 12 which communicates through the bore 22 of the sub with the bore of the tubing string 10 and extends downwardly from the upper portion of said body.

The upper end of the bore 12 is enlarged, forming an annular shoulder 28, which is beveled downwardly and whose function will be described hereinafter. The lower end of the bore 12 communicates with the vertical, elongated slot or recess 13 which extends through the wall of the drill body and which has a width slightly less than the diameter of the bore 12. The slot is disposed in a vertical plane parallel to the two flat surfaces 27 and extends to a point substan-

tially even with the lower ends of said flat surfaces.

The inclined deflector member 14, having substantially the same width as the slot 13, is pivotally mounted on the back wall of said recess so as to swing in a vertical plane. The upper or inner end of the deflector member terminates in a transverse cylindrical ridge or pin 29 which engages within a transverse semi-cylindrical groove 30 formed in the opposite side of the body. The pin 29 is held within the groove 30 by means of a plate 31 which partially overlies a longitudinal portion of said pin and is held in position by bolts or screws 32 which securely fasten the plate to the back wall of the recess. Obviously, the pin 29 and groove 30 form a roller joint which permits the deflector 14 to swing freely. The coil spring 15 is mounted beneath said deflector member so as to constantly urge said member in an upward direction, as hereinbefore pointed out, and a keeper plate 33 is mounted flush with the exterior surface of the body 11 by means of a bolt 34, so as to engage the outer end of said member and limit its upward movement to a position where said outer end does not project beyond a point flush with the exterior surface of the body 11. The upper face of the deflector member is dished so as to force the sampling tube in an outward direction as it is lowered through the bore 12. When the sampling tube engages the deflector, the latter will swing inwardly, or give slightly, so as to lessen the shock to the sampling tube.

It is pointed out that this member serves an important part in safeguarding the operation of the sampling device. If, for any reason, the sampler 18 should become wedged or stuck in the bore 12, it would be necessary to raise the entire sampling device A to the surface in order to dislodge said sampler. In a stuck position, the sampling tube 20 would project outwardly into the well bore, and would be in danger of being broken off as the sampling device encounters the lower end of the casing string. This possibility is eliminated by having the deflector member hinged and maintained in an upwardly swung position by the spring 15. In the event, the sampling tube 20 strikes an obstruction in its upward travel, it would be free to compress the spring 15 and swing the member 14 inwardly, thereby allowing said tube to swing inwardly to a point where it would clear said obstruction. This arrangement is necessary only where the sampler becomes stuck within the drill body and serves merely to safeguard the device.

When the drill body is being lowered into the well, it is necessary to provide some means for plugging the bore 12, so that the same will not become clogged with foreign matter, and for this purpose the plug 17 is provided. The plug is formed of an elongated, cylindrical bar or rod having its upper portion enlarged to form an annular shoulder 35 near its middle or intermediate portion. The shoulder 35 is designed to engage the shoulder 28, whereby the plug is supported within the bore 12 and prevented from passing therethrough. The upper end of the plug is formed with a fishing neck 36 which projects into the bore 22 above the annular grooves 24 of the sub 21 and allows the plug to be removed, when desired, by any suitable type of fishing tool (not shown). The plug is left in its position within the drill body while the well is being drilled and it is pointed out that said plug possesses sufficient weight as to prevent its being displaced by

fluid or drilling mud passing upwardly through the device. However, when it is desired to take samples of the formation through which the well bore extends or has passed, the plug is removed by means of a suitable fishing tool (not shown) and replaced by the sampler 18, as shown in Figure 2.

The elongate upper portion or mandrel 19 of the sampler 18 has a transverse, vertical notch or slot 37 formed in its lower end. A sampling member 38, having an axially-extending shank 39 provided on its upper end, is suspended from the mandrel, said shank being pivotally mounted within the notch 37 by a pin 40. The shank 39 is built up or enlarged at its lower end to form a screw-threaded pin 41, upon which is mounted by internal screw-threads 42, the elongate sampling tube 20, which has an axial bore 43 for receiving the well formation sample and which has the peripheral edge of its outer or free end 44 sharpened for cutting into the formation. An opening 45 communicates from the bore 43, through the pin 41, to the space outside the surface of the web 39, to allow any fluid present within the bore 43 to escape when a sample is taken. A shear pin 46 is mounted so as to pass through the lower portion of the notch 37 and the upper portion of the web 39, and thus hold the sampling member in a vertical position. As the sampler 18 is lowered through the bore 12, the combined force of the spring 15 and the weight of said sampler bearing against the deflector member 14 will shear the pin 46 thereby allowing the sampling tube 20 to move out into engagement with the well formation. It is pointed out, that if a formation is encountered that is too hard to allow the sampling tube to pass therewith, the spring 15 will yield sufficiently to allow the sampling tube to ride down the wall of the well hole with the drill body until a softer formation is encountered.

The mid-portion of the mandrel 19 is surrounded by a tubular sleeve 47 which fits snugly and securely over the mandrel, said sleeve having a sliding fit within the bore 12 of the drill body, and extending downwardly substantially to the top of the recess 13. The upper end of the mandrel carries internal screw-threads 48 which engage complementary screw-threads on the inner wall of the sleeve 47, thus securely fastening said mandrel within said sleeve. The sleeve is enlarged in outside diameter at a point in a transverse plane with said screw-threads, to form an annular shoulder 49 which engages and is supported by the shoulder 28, thereby supporting the sleeve and mandrel within the bore 12. The lower end of the sleeve is cut at an angle thus forming an elliptical bottom opening 50, and an elongate slot 51 extends vertically from the highest point of said elliptical opening up the side wall of the sleeve. A screw-threaded pin 52 is mounted in a transverse screw-threaded opening 53 in the side wall of the drill body 11 at a point slightly below the shoulder 28 and in a vertical plane with the recess 13. The pin 52 projects a short distance into the bore 12 so as to substantially abut the periphery of the mandrel 19. Obviously, as the mandrel and the sleeve are lowered into the bore 12, the lower edges of the sleeve will engage the pin 52. Thereupon, the pin will ride up the edges of the elliptical opening 50, and cause the mandrel and the sleeve to rotate until the pin and the slot 51 are in vertical alignment. Then the sleeve and the mandrel may pass downwardly until the shoulder 49 engages the shoulder 28. Since the sleeve and the mandrel are rigidly se-

cured together, this alining action will cause the mandrel to come to rest in the same position every time it is lowered into the bore 12. Therefore, it is assured that the sampling member 38 will always be in a position whereby it may swing outwardly into engagement with the wall of the well hole. It is desirable to place a small bumper plate 47', having substantially the same thickness as the walls of the sleeve 47, at a point on the surface of the mandrel in vertical alinement with the slot 51 and spaced downwardly therefrom. This plate maintains the sampler alined in the bore 12 and obviates the possibility that the lowermost edge or point of the elliptical opening 50 will ride over the outer extremity of the pin 52 and jam the sampler within said bore. As seen in the drawings, specifically Figure 6, this plate does not in any way interfere with the action of the pin 52 in alining the sampler within the bore 12.

The upper portion of the sleeve 47 extends upwardly some distance into the sub 21 and has a short cylindrical member or rod 54 slidably mounted therein in a longitudinal position. A transverse notch or slot 55 is provided on the upper end of the mandrel above the screw-threads 48, and is formed in the same transverse vertical plane as the notch 37 at the lower end of said mandrel. A latching member 56 is pivotally mounted in the slot 55 on a pin 57 extending transversely thereof. The latching member is designed to swing outwardly through a rectangular opening 58 formed in one side wall of the sleeve 47. The upper end of the latching member is curved outwardly toward its outside edge, thus forming a point or corner 59 which will engage beneath one of the shoulders 25 when the latch member is in its outwardly swung position. The central portion of the latch member is provided with a transverse opening 60 having its upper wall extended and reduced in size so that a pin passing through said opening would force the latch to assume a vertical position when said pin is moved upwardly. The lower end of the cylindrical rod 54 is formed with a transverse slot 61 within which the latch member 56 is free to swing, and carries in its central portion a transverse pin 62 which passes through the opening 60 of said latch member. As has been hereinbefore stated, the rod 54 is free to slide within the sleeve 47. Thus, as seen in Figure 7, the rod in its downward position, rests on the top of the mandrel 19, and the pin 62 is in the enlarged portion of the opening 60. In this position, the latch member is free to swing outwardly and engage beneath one of the shoulders 25, and thus secure the mandrel within the bore 12 so that any downward movement of the drill body will necessarily cause the mandrel to move downwardly therewith. When the rod 54 is raised, the pin 62 will ride upwardly in the opening 60, and, because of the reduced size and slanted walls of the opening, force the latch member to move back to a central or vertical position, as shown in Figure 8. After this operation, the latch member is not engaged beneath the shoulder 25 and the entire sampler 18 is free to be withdrawn from the bore 12.

It is pointed out that the sampler can be lowered into, and raised from, the well bore by any desirable means. It may be run on a wire line or, as shown in the drawings, the upper portion of the rod 54 may be provided with a fishing neck 63, whereby suitable fishing tools (not shown) may be lowered into the well hole to remove the said sampler. Also, it is desirable to

have a guide member or ridge 64 mounted on the back portion of the drill body, diametrically opposed from the opening of the recess 13, said guide member serving to keep the tool centered within the well bore so that the sampling tube 20 must necessarily engage the wall of the well bore. The guide member is shown in the drawings as fastened to the drill body by bolts 65, but any suitable fastening means may be satisfactorily used.

It is necessary to make some provision for allowing the drilling fluid to be pumped down the tubing string to the drill bit and yet have the axial bore of the drill body unobstructed so that coring operations may be facilitated. For this purpose, a pair of diametrically opposed vertical grooves 66 are provided in the bore of the sub 21, as shown in Figure 3 and Figure 6. These grooves lie in a vertical plane at a right angle to the vertical plane in which the latching member 56 lies, whereby it is impossible for the latter to engage in one of said grooves and thus fail to anchor the sampler 18 within the bore 12. A pair of diametrically opposed ports 67 communicate between the box 26 and the spaces exterior of the flattened surfaces 27. When the sub is engaged within the box 26, the grooves 66 and the ports 67 are in registration, whereby communication is set up between said grooves and said ports. Elongate members 68, substantially semi-circular in cross-section, are secured to the exteriors of the surfaces 27 by welding or other suitable means, and extend vertically throughout the length thereof. These members form passages or water-courses for conducting the drilling fluid from the ports 67 to the lower end of the drill body 11. Registering vertical ports 69 are provided in the lower end of the drill body to conduct fluid to the bottom thereof. In this manner, the drilling fluid may be conducted from the tubing 10, through the grooves 66, the ports 67, the passages 68, and the ports 69, to the lower or drilling end of the device, whereby the bore of said device may be utilized for accommodating sampling equipment.

When, in the course of drilling operations, it is desired to take core samples of the formation through which the well bore is passing, a fishing tool (not shown) is lowered into the well bore until said tool engages the fishing neck 36 on the top of the plug 17. The plug is withdrawn from the bore 12 and the sampler 18 is lowered in its stead. When the sampler strikes the dished and inclined upper surface of the deflector member 14, the pin 46 will be sheared, as described hereinbefore, and the sampling member 38 will move outwardly through the opening of the recess 13 so that the sampling tube 20 is forced into engagement with the well formation. At the same time the latching member 56 will be free to swing to one side into engagement with one of the notches 25. It is to be noted that the tendency of the latch will be to swing in this direction since its center of gravity lies in a vertical plane on that side of the pin 57. After the latch has swung into position, the sampler is held securely within the bore 12 by the action of said latch and the engagement of the shoulder 28 by the shoulder 49 on the mandrel. When this operation has been completed, the drill body 11, carrying the sampling mechanism, is lowered further

into the well hole, thereby forcing the sampling tube 20 into the formation in a horizontal position as shown in Figure 5. The subsequent raising of the drill body will withdraw the sampling tube, along with its sample, from the well formation. A fishing tool (not shown) may then be utilized to engage the fishing neck 36 and release the latch member 56 as hereinbefore described, whereby the sampling mechanism may be withdrawn from the well bore.

Obviously, by these operations and with this device, samples may be taken at any desired time or point during the drilling operation. Also, if desired, the drill body can be raised within the well bore, and samples of the various formations and strata, through which the drill body has already passed, may be taken. As pointed out hereinbefore, any type of drill bit may be mounted on the lower end of said drill body, and, since the drilling fluid is by-passed through the water-courses 68 and the sampling mechanism is separate therefrom, both drilling and sampling operations may be carried out substantially simultaneously. The device is simple and sturdy in its operation, and, due to the action of the guide member 64 in centering the device in the well bore, the operator is always assured of obtaining a core sample.

Various changes and modifications may be made in the elements described herein without departing from the principles taught by this invention.

What I claim and desire to secure by Letters Patent is:

35. 1. A sidewall sampling device which is adapted to be lowered into a well bore and includes, a housing having a longitudinal opening, sampling means designed to be passed through said opening, means for locking said sampling means in position within said opening, a deflector plate at the lower end of said opening for forcing said sampling means into engagement with a side wall of the well bore said deflector plate being pivotally mounted and having resilient means 40 compressed therebehind, and means for removing said sampling means to the surface of the well while the housing remains within the well bore.

2. A side wall sampling device which is adapted to be lowered into a well bore and includes, a drill body having a longitudinal opening therein, a drill bit mounted on the lower extremity of said drill body, sampling means designed to be passed through said opening, means for locking said sampling means in position within said opening, a deflector plate for forcing said sampling means into engagement with a side wall of the well bore, said deflector plate being resiliently mounted within the drill body, and means for removing said sampling means to the surface of the well while the drill body remains within the well bore.

3. In a side wall sampling and testing tool, a body to receive and deflect the sampler member through a lateral opening therein, an arm pivoted in said opening, and spring means to normally hold said arm in position to deflect the sampler but yieldable to allow the sampler to move in flush with said body by the depressing of said arm.

W. NORMAN OSWALD.
